Application June 22, 1938, Serial No. 215,199
In Great Britain June 30, 1937

24 Claims. (Cl. 207—2)

This invention relates to continuous metal extrusion machines of the kind in which plastic metal is driven into an extrusion chamber and thence through an extrusion orifice by a rotating screw-threaded impelling device which comprises an inner member and a tubular, though not necessarily cylindrical, outer member, and of which the axis is horizontal or is inclined at a small angle to the horizontal. Such a machine will hereinafter be referred to as a "horizontal metal extrusion machine of cylindrical type" to distinguish it from extrusion machines having a vertical axis and also from extrusion machines with an impelling device of disc form.

In horizontal metal extrusion machines of cylindrical type a drive is applied to the rotatable part of the impelling device at a point to the rear of the extrusion chamber. For this purpose an opening is provided in the lower part of the extrusion machine casing of which a part, instead of merely housing the impelling device, may in some cases actually constitute the outer member of the impelling device. Generally the apertured part of the casing is surrounded by a downwardly extending wall forming a hollow pedestal support for the machine and serving as a housing for a gear drive to the rotatable part of the impelling device. In such machines heavy thrust loads are exerted by the plastic metal on the front wall of the extrusion chamber and on the stationary and rotating parts of the impelling device, the load on the rotating member having to be taken up by a large thrust bearing. These loads result in the casing being subjected to heavy tensile stresses in a longitudinal direction.

It has been found that the casings of such machines unless heavily reinforced by the addition of special strengthening members in the neighbourhood of the apertured part of the casing, distort under the heavy thrust loads exerted upon them to such an extent that, in the case of machines of the kind in which the concentric members constituting the impelling device are not relatively supported at their front ends, these members are caused to assume a non-parallel position. When inner and outer dies are used this results in that the inner die or point is no longer concentric with the outer die or matrix, and the product, instead of having a uniform wall thickness, has a wall that is thicker on the upper side than on the lower side of the product as it leaves the machine. In cases where supports extending between the relatively rotatable concentric members forming the impelling

device are provided at the delivery end of the device, distortion of the casing produces abnormal wear on the supporting surfaces and eventually eccentricity of the point and matrix. It is an object of this invention to provide an improved construction of horizontal extrusion machine of the cylindrical type which avoids the possibility of distortion of the casing under the thrust loads to which it is subjected without the necessity for providing special strengthening members.

It has been found that casings of horizontal extrusion machines of the cylindrical type as at present constructed also distort due to temperature differences in the various parts of the casing. Generally the underneath part of the casing in the region of the supporting pedestal will be cooler than the upper part. The consequent unequal expansion of these parts of the casing will result in distortion of the casing, and hence in eccentricity of the parts of the impelling device and of the dies or in abnormal wear of the supporting surfaces provided to maintain the parts concentric. This eccentricity will generally be in the reverse direction to that due to the thrust load but the two effects will not counterbalance one another. Unequal cooling of different parts of the casing also leads to unequal cooling of the plastic metal at different parts of the circumference. Generally the effect of this is to increase the rate of extrusion in one side of the impelling device. This is naturally disadvantageous, and may lead to eccentricity of the parts of the impelling device and to imperfections in the extruded product. It is a further object of the present invention to provide an improved form of construction which avoids such temperature differences and ensures that the casing expands symmetrically thus eliminating the possibility of its distortion.

In our improved form of construction of extrusion machine of the screw thread impeller type, the parts of the casing which houses the impelling device and the driving wheel thereof and which are subjected to the thrust loads exerted by the plastic metal are made symmetrical about the axis of the impelling device and, preferably, also symmetrical in section in any plane containing the said axis. By the term "symmetrical" we mean symmetrical apart from minor apertures such as bolt holes, oil channels and the like, in other words, that the general form of the part of the casing subjected to thrust loads is symmetrical. The effect of this is that the extension or compression of the casing due to the

5 thrust load exerted upon it is equal at all diametrically opposite points so that no eccentric distortion thereof takes place and hence no eccentric displacement of the impelling parts and dies nor excessive wear of the guide surface or surfaces (if any) supporting the front end of the members constituting the impelling device.

10 Where the part of the casing in the vicinity of the supports is not subjected to thrust loads exerted by the plastic metal, it is not essential, from the point of view of avoiding distortion due to thrust loads, for it to be symmetrical but it is preferably made so to avoid distortion due to thermal stresses and asymmetrical driving 15 stresses, and to avoid unequal extrusion at different parts of the circumference. This preferred form of construction will generally necessitate the provision of separate supporting members. These are preferably heat insulated from 20 the casing. The symmetrical form of construction will also necessitate a modified form of drive as compared with the forms that have been proposed or used for machines of this kind.

25 By way of example the invention will be further described with reference to the accompanying drawings wherein,

30 Figure 1 is a longitudinal section, taken on the line I—I in Figure 2, through one form of extrusion machine constructed in accordance with the invention,

Figure 2 is a front end elevation of the machine shown in section in Figure 1,

35 Figure 3 is a side view partly in longitudinal section and partly in elevation of a modified form of extrusion machine constructed in accordance with the invention,

Figure 4 is a rear end elevation of the machine shown in Figure 3.

40 Figure 5 is a fragmental view, partly in section on the line V—V in Figure 4 and partly in elevation looking in the direction of arrow X in Figure 4, of the machine shown in Figures 3 and 4,

45 Figure 6 is a fragmentary cross-section showing a modified form of the coupling between the machine casing and the gear casing shown in Figure 3,

50 Figure 7 is a plan view, partly in section on the line VII—VII in Figure 8 of a second type of extrusion machine constructed in accordance with the invention,

Figure 8 is a rear end elevation of the machine shown in Figure 7, and

55 Figure 9 is a fragmental cross-section taken on the line IX—IX of Figure 8.

The machine shown in Figures 1 and 2 of the drawings will first be described. It comprises a rotatable tubular member 1 which works in a cylindrical casing 2a and has on its outer surface 60 helically extending projections 3 which co-operate with longitudinally extending projections 4 on the adjacent inner surface of the casing to form a screw thread metal impelling device. The front end wall 5 of the casing is furnished 65 with an extrusion die or matrix 6 and an inner die or point 7, co-operating with the matrix to form an annular extrusion orifice, is mounted on the end of a stationary tubular member 8 which passes co-axially through the rotating 70 tubular member 1. Metal in a molten state is fed into the space between the casing and the rotating tubular member through the inlet passage 9 and is cooled sufficiently to co-operate with the projections 3 and 4 by which it is moved forward in a plastic condition into the extru-

75 sion chamber 10 and out through the extrusion orifice. Helically extending projections 3a and longitudinally extending projections 4a are also provided on the inner surface of the rotating member and on the adjacent outer surface of the 80 tubular member 8, respectively, to constitute an auxiliary screw thread impelling device which is supplied with molten metal through ports 9a in the rotating member 1. An example of a 85 machine of this type is described in the specification of British Patent No. 430,006. Hitherto the stationary member 8 has been supported from the rear wall of the machine casing 2 and the 90 thrust on the rotating tube 1 has been taken up by the rear wall of the casing through a ball 15 thrust bearing disposed between the rear wall and an abutment on the rear end of the tube, and the tube has been driven by a wheel mounted on the rear end thereof to which a drive was applied through an aperture in the bottom of 20 the casing by gear wheels housed in a hollow pedestal supporting the casing. With this construction the machine casing is subjected to tension throughout its length due to the thrust loads. In the improved construction shown in 25 Figures 1 and 2, there is provided on the wall of the machine casing an inwardly extending flange 11 which is located in front of a driving wheel 12 mounted on the rear end of the rotating part 1 of the impelling device and a ball 30 thrust bearing 13 is inserted between the front face of the flange 11 and the rear face of a flange 14 keyed on to the sleeve 1 and abutting against the rear face of a collar 15 on that sleeve. In this way the unsymmetrical part of the casing, 35 i. e. the part to the rear of the flange 11 is relieved of any thrust exerted by the rotating part of the impelling device. The unsymmetrical part of the casing is relieved of thrust exerted by the inner fixed member 8 by anchoring it longitudinally to the rotating member 1 instead of to the rear wall 16 of the casing. This is done by securing to the rear face of the driving wheel 12 a tubular member 17 supported in a cylindrical bearing 18 formed in the rear end of the casing 40 and by inserting a thrust bearing 19 between the front face of an inwardly extending flange 20 at the rear end of the tubular member 17 and the rear face of a flange 21 keyed on to the rear end of the stationary member 8 and held in 45 position by the nut 22. The driving wheel 12 is positively secured against the tendency to rearward movement in an axial direction by a collar 23 screwed on to the rear end of the rotating part 1 and the inner concentric part 8 is anchored against rotation by being loosely keyed or 50 loosely splined to the rear wall 16 of the casing as shown at 24. With the arrangement above described the thrust on the stationary member 8 is transferred through the flange 21, tube 17, 60 wheel 12 and collar 23 to the rotating tube 1 and through this tube, collar 15, flange 14 and bearing 13 to the inwardly extending flange 11 on the casing, the thrust exerted directly on the rotating member is transferred through collar 65 15, flange 14 and bearing 13 to the flange 11 also, and the thrust on the front end wall 5 is transferred to the casing through the nut 25. Consequently the only part of the casing subjected to 70 stresses due to the thrust loads is the flange 11. This part of the casing and all the other parts of the machine by which the various thrust loads are transferred to this part of the casing are 75 tubular members of circular cross-section and

consequently do not distort asymmetrically under the thrust load. The driving wheel 12 is in the form of an externally toothed gear wheel and the part of the casing to the rear of the flange 11 is not symmetrical but is extended downwards to form a support 26 in the form of a hollow pedestal in which is rotatably mounted a driving shaft 27 carrying a gear wheel 28 which engages with the teeth of the wheel 12. It will be seen that the casing 2 is divided transversely into four parts 2a, 2b, 2c and 2d in order to facilitate assembly of the machine. These parts are secured together by the bolts 29.

The arrangement shown in Figures 1 and 2 does not however avoid temperature stresses, asymmetrical driving stresses and unequal extrusion due to unequal cooling. To avoid these disadvantages there is provided a modified form of construction which is shown in Figures 3, 4 and 5 of the drawings to which reference will now be made. In this form of construction the part of the machine to the front end of the flange 11 is similar in all material respects to the corresponding part of the machine shown in Figures 1 and 2 but the externally toothed driving wheel 12 of the previously described machine is replaced by a driving wheel 31 in the form of a flanged collar, the rear end wall of the part 2d of the casing is omitted and a drive applied to the inwardly extending flange 20 on the tubular member 17 secured to the rear face of the driving wheel 31 by bolts 32. This permits the parts 2c and 2d of the casing to be of circular cross-section throughout, since no opening in the circumferential wall thereof is required in order to permit of the application of a drive. The casing is then supported in a pair of cradles 33 which are heat insulated from the casing, for instance, by insertions 34 of asbestos material or the like. The tubular member 17 forming a torque tube is driven by a second driving wheel 35 housed in a cylindrical casing 36 and rotatably mounted on a stub shaft 37 projecting from the end wall 38 of the casing. The wheel 35 and its casing are supported by a pedestal 39 in such a manner that the axis of rotation of the wheel 35 is coincident with that of the extrusion machine. The wheel 35 is coupled to the torque tube 17 by a flexible coupling constituted by pins 40 which project from the rear face of the flange 20 and enter rubber lined recesses 41 in the adjacent face of the wheel. Rotation is imparted to the wheel 35 by means of a pinion 42 driven from a suitable gear box which is not shown. Rotation of the member 8 carrying the inner die is prevented by loosely splining its rear end to the hollow stub shaft 37 which is positively secured to the end wall of the gear casing by screws. The machine casing 2 of which the part 2a forms the stationary part of the impelling device is positively held against rotation by providing on the rear extremity of the cylindrical wall of the part 2d a series of dogs 43 which engage with corresponding dogs 44 on the adjacent fixed wall of the casing 36. Preferably actual metallic contact of the machine casing 2 and the second driving wheel casing 36 is prevented by the interpolation of heat insulating pads 45 between the engaging surfaces of the dogs. Alternatively, as shown in Figure 6, the machine casing 2d may be restrained from rotating by a series of pegs 46 which project from the front end face 47 of the casing 36 and enter holes 48 in an outwardly turned flange 49 on the casing 2d. The holes are lined with heat

insulating material 50 and heat insulating pads 45 are placed between the adjacent surfaces of the two casings.

In the extrusion machine which is shown in Figures 7, 8 and 9 of the drawings, the screw thread impelling device comprises two longitudinally extending concentric members, 51 and 52, having helically extending ribs 53 on their adjacent surfaces, the ribs on the one member being of opposite hand to those on the other. The inner member 51 is stationary and the outer member 52 is rotatably driven by means of a driving wheel 54 mounted on the rear end of a sleeve member 55 which in turn is mounted on the member 52. The rotating parts 52, 54 and 55 are supported in bearings in a frame or casing 56. At its rear end the rotating sleeve 52 enters the stationary wall 57 of the feed chamber 58 formed in the back cover member 59, a sealing gland 60 being provided between the wall of the feed chamber and the rotating sleeve 52. At its front end the sleeve 52 makes a running joint 61 with the stationary wall 62 on the front cover 63 in which the extrusion chamber 64 is formed. The inner stationary member 51 extends rearwardly through the feed chamber 58 and is secured to the rear wall 65 thereof and extends forwardly into the extrusion chamber 64 and is supported at its front end by pads 66 constituted by the front extremities of the helical ribs 53 provided on the outer surface of the member. When the machine is to be used for the production of tubing the front end of the stationary member 51 carries an inner die 67 which co-operates with an outer die 68 in the front wall of the extrusion chamber to form an annular extrusion orifice. Molten metal is fed continuously into feed chamber 58 from whence it flows into the space between the members 51 and 52 where it is cooled so that it acquires sufficient rigidity to co-operate with the surface of the concentric members and be driven forward by them into the extrusion chamber 54 and out through the extrusion orifice. The thrust exerted on the inner member 51 is transferred directly to the back cover 59 and the thrust exerted on the rotating member 52 is transferred to the frame 56 through the sleeve 55 and the bearing 69 inserted between an outwardly extending flange 70 on the sleeve 55 and an inwardly extending flange 71 on the frame 56. An example of a machine of this type is described in the specification of U. S. Patent No. 2,051,688.

Hitherto in machines of the kind described in the preceding paragraph, the frame 56 has not been made symmetrical but has been extended downwards to form a support in the form of a hollow pedestal in which are housed a pair of gear wheels by which the drive is imparted to the wheel 54. In the improved construction of the machine shown in Figures 7 and 8 of the drawings, all parts of the casing subjected to thrust loads are of symmetrical form, the central portion 56 which carries thrust loads exerted by the plastic metal on the impelling device and in which the driving wheel 54 is housed being of circular cross-section except for the provision of two small pockets 72 located adjacent the periphery of the driving wheel and on diametrically opposite sides thereof. These pockets 72 each house a gear wheel 73 mounted on a shaft 74 supported in bearings 75 in the walls of the pocket. The shafts 74 extend through the rear walls of the pockets and are driven through flexible couplings 76 and a gear box 92, which is

located clear of the machine casing, by a single driving shaft 77 which is capable of a limited movement in a vertical direction. In the plan view of the gear box one of the two covers 91 and 5 part of the other cover and also parts of the gearing have been removed to expose the interior of the gear box. The gear box 92, comprises a pinion 78 which is mounted on the driving shaft 77 and engages two spur wheels 79 10 each of which in turn drives through a co-axial pinion 80 and a spur wheel 81, which is loosely mounted on the shaft 93 as shown in Figure 9, a spur wheel 82 on the shaft 83 to which the shaft 74 is coupled. This arrangement gives a 15 balanced drive. The extrusion machine itself is supported on feet 84 which extend horizontally from the side walls of the two pockets 72 in the machine casing. As will be seen from Figure 8 these feet are symmetrical about a horizontal 20 plane containing the machine axis. This symmetrical form of casing avoids unsymmetrical distortion thereof due to the thrust load, which distortion would cause mis-alignment of the several bearings and heavy wear on the gland 60 25 and other bearing surfaces. Preferably heat insulation 85 is inserted between each supporting foot and the pedestal 86 on which the foot rests and the bolts 87 by which the frame is secured to the pedestal 86 are also heat insulated by 30 insulation 88. Heat insulation 89 is also preferably inserted between the two parts of the flexible coupling and between the coupling bolts 90 and the parts in engagement therewith. By this 35 means unsymmetrical cooling of the casing of the machine is reduced and hence the tendency for it to distort under temperature stresses. The provision of the heat insulation also reduces unsymmetrical cooling of the outer wall of the extrusion chamber.

40 It will be appreciated that the machine shown in Figures 3-5 of the drawings may be supported by symmetrically formed feet of the type described in the preceding paragraph instead of by one or more cradles. In this case the need for 45 a positive coupling between the machine casing and the gear casing is avoided.

What I claim as my invention is:

1. In a horizontal metal extrusion machine comprising a screw thread impelling device, consisting of an inner member and a tubular outer member, by which the metal to be extruded is driven forward in a plastic state, a driving wheel on one of the members of the impelling device, 50 and a casing housing the impelling device and said driving wheel, the parts of said casing that are subjected to thrust loads exerted by the plastic metal being symmetrical about the axis of the impelling device.
2. In a horizontal metal extrusion machine comprising a screw thread impelling device, consisting of an inner member and a tubular outer member, by which the metal to be extruded is driven forward in a plastic state, a machine 55 casing which houses the impelling device and a driving wheel therefor mounted on one of the members thereof and which is symmetrical about the axis of the impelling device throughout its length, and means for applying a drive to the driving wheel of the impelling device through an aperture in the rear end of said casing.
3. In a horizontal metal extrusion machine comprising a screw thread impelling device, consisting of an inner member and a tubular outer member, by which the metal to be extruded is 75

driven forward in the plastic state, a machine casing which houses the impelling device and a driving wheel therefor mounted on one of the members thereof and which is symmetrical about the axis of the impelling device throughout its 5 length, a second driving wheel which is located outside said machine casing and supported independently thereof and is concentric with the driving wheel within the casing, and means passing through an aperture in the rear end of 10 said machine casing for coupling together the internal and external driving wheels.

4. In a horizontal metal extrusion machine comprising a screw thread impelling device, consisting of an inner member and a tubular outer 15 member, by which the metal to be extruded is driven forward in a plastic state, a machine casing which houses the impelling device and a driving wheel therefor mounted on one of the members thereof and which throughout its 20 length is symmetrical about the axis of the impelling device and also symmetrical in section in any plane containing the said axis, and means for applying a drive to the driving wheel of the impelling device through an aperture in the rear 25 end of said casing.

5. In a horizontal metal extrusion machine comprising a screw thread impelling device, consisting of an inner member and a tubular outer member, by which the metal to be extruded is 30 driven forward in a plastic state, a machine casing which houses the impelling device and a driving wheel therefor mounted on one of the members thereof and which throughout its 35 length is symmetrical about the axis of the impelling device and also symmetrical in section in any plane containing the said axis, a second driving wheel which is located outside said machine casing and supported independently thereof and is concentric with the 40 driving wheel within the casing, and means passing through an aperture in the rear end of said machine casing for coupling together the internal and external driving wheels.

6. In a horizontal metal extrusion machine 45 comprising a screw thread impelling device, consisting of an inner member and a tubular outer member, by which the metal to be extruded is driven forward in a plastic state, a machine casing which houses the impelling device and a driving wheel therefor mounted on one of the members thereof and which is of substantially circular cross-section throughout its length and is apertured at its rear end, means for applying a drive to the driving wheel of the impelling device 55 through the aperture in the rear end of said casing, and at least one separate supporting cradle for supporting said casing.

7. In a horizontal metal extrusion machine comprising a screw thread impelling device, consisting of an inner member and a tubular outer member, by which the metal to be extruded is 60 driven forward in a plastic state, a machine casing which houses the impelling device and a driving wheel therefor mounted on one of the members thereof and which is of substantially circular cross-section throughout its length and is apertured at its rear end, means for applying a drive to the driving wheel of the impelling device through the aperture in the rear end of 65 said casing, at least one separate supporting cradle for supporting said casing, and heat insulation interposed between said casing and said supporting cradle.

8. In a horizontal metal extrusion machine 75

- comprising a casing which houses or forms part of a rotating screw thread impelling device, comprising a rotatably driven inner member and a stationary tubular outer member, by which the metal to be extruded is driven forward in a plastic state, a driving wheel on the driven inner member, means for imparting rotary movement to said driving wheel through an aperture in the casing, a flange located adjacent the driving wheel and extending inwardly from the casing, and means for transferring the axial thrust exerted on the driven inner member by the plastic metal to said flange on the casing, the part of the casing in front of the said flange being symmetrical about the axis of the impelling device.

9. In a horizontal metal extrusion machine comprising a casing which houses or forms part of a rotating screw thread impelling device, comprising a rotatably driven inner member and a stationary tubular outer member, by which the metal to be extruded is driven forward in a plastic state, a driving wheel on the driven inner member, means for imparting rotary movement to said driving wheel through an aperture in the casing, a flange located adjacent the driving wheel and extending inwardly from the casing, and means for transferring the axial thrust exerted on the driven inner member by the plastic metal to said flange on the casing, the part of the casing in front of the said flange being of substantially circular cross-section.

10. In a horizontal metal extrusion machine comprising a casing which houses or forms part of a rotating screw thread impelling device, comprising a rotatably driven inner member and a stationary tubular outer member, by which the metal to be extruded is driven forward in a plastic state, a driving wheel on the driven inner member, means for imparting rotary movement to said driving wheel through an aperture in the casing, a flange located adjacent the driving wheel and extending inwardly from the casing, and means for transferring the axial thrust exerted on the driven inner member by the plastic metal to said flange on the casing, the part of the casing in front of the said flange being of substantially circular cross-section.

11. In a horizontal metal extrusion machine comprising a casing which houses or forms part of a rotating screw thread impelling device, comprising a rotatably driven inner member and a stationary tubular outer member, for driving plastic metal forward into an extrusion chamber and out through an annular extrusion orifice formed by inner and outer dies, a support for the inner die, means for transferring the thrust on the inner die and its support to the rotatably driven inner member, a driving wheel on the driven inner member, means for applying rotary movement to said driving wheel through an aperture in the casing, a flange located adjacent said driving wheel and extending inwardly from the casing, and means for transferring the thrust on the driven inner member to said flange, the part of the casing in front of said flange being of substantially circular cross-section.

12. In a horizontal metal extrusion machine comprising a casing which houses or forms part of a rotating screw thread impelling device, comprising a rotatably driven inner member and a stationary tubular outer member, for driving plastic metal forward into an extrusion chamber and out through an annular extrusion orifice formed by inner and outer dies, a support for the inner die, means for transferring the thrust on

the inner die and its support to the rotatably driven inner member, a driving wheel on the driven inner member, means for applying rotary movement to said driving wheel through an aperture in the casing, a flange located in front of said driving wheel and extending inwardly from the casing, and means for transferring the thrust on the driven inner member to said flange, the part of the casing in front of said flange being of substantially circular cross-section.

13. In a horizontal metal extrusion machine comprising a casing which houses or forms part of a screw thread impelling device constituted by inner and outer concentric tubular members of which the inner is driven in rotation and by which plastic metal is driven forward and through an annular extrusion orifice constituted by inner and outer dies, a support for the inner die extending rearwardly of the driven inner member, a flange on a part of said support extending beyond the driven member, a driving wheel mounted on the driven inner member, means for applying rotary movement to said driving wheel through an aperture in the casing, a tubular member secured to the rear face of said driving wheel, an inwardly extending flange on said tubular member, a thrust bearing interposed between said flange on said support and said inwardly extending flange, an inwardly extending flange on the casing adjacent the driving wheel and means for transferring the axial thrust exerted on the driven inner member by the plastic metal to the said flange on the casing, the part of the casing in front of the said flange on the casing being of substantially circular cross-section.

14. In a horizontal metal extrusion machine comprising a casing which houses or forms part of a screw thread impelling device constituted by inner and outer concentric tubular members of which the inner is driven in rotation and by which plastic metal is driven forward and through an annular extrusion orifice constituted by inner and outer dies, a support for the inner die extending rearwardly of the driven inner member, a flange on a part of said support extending beyond the driven member, a driving wheel mounted on the driven inner member, means for applying rotary movement to said driving wheel through an aperture in the casing, a tubular member secured to the rear face of said driving wheel, an inwardly extending flange on said tubular member, a thrust bearing interposed between said flange on said support and said inwardly extending flange, a flange on the driven member located in front of said driving wheel, an inwardly extending flange on the casing located between said driving wheel and said flange on the driven member, and a thrust bearing interposed between said flange on the casing and said flange on the driven member, the part of the casing in front of the said flange on the casing being of substantially circular cross-section.

15. In a horizontal extrusion machine comprising a casing which houses or forms part of a rotating screw thread impelling device, comprising an inner member and a tubular outer member, by which the metal to be extruded is driven forward in a plastic state, a driving wheel on one of the members constituting the impelling device, means for imparting rotary movement to said driving wheel through an aperture in the casing, a flange located adjacent the driving wheel and extending inwardly from the casing, and means for transferring the axial thrust ex-

ereted on the driven member by the plastic metal to said flange on the casing, the part of the casing in front of said flange and the part housing said driving wheel being symmetrical about the machine axis.

16. In a horizontal metal extrusion machine comprising a casing of substantially circular cross-section which houses or forms part of a screw thread impelling device constituted by inner and outer concentric tubular members of which the inner is driven in rotation and by which the plastic metal is driven forward and through an annular extrusion orifice constituted by inner and outer dies, a support for the inner die extending rearwardly of the driven inner member, a driving wheel mounted on the driven inner member, a torque tube coupled to said driving wheel and extending rearwardly thereof, means for applying through an aperture in the rear end of the machine casing, a drive to the rear end of said torque tube, an inwardly extending flange on said torque tube, an outwardly extending flange on a part of said inner die support extending beyond the driven member, a thrust bearing interposed between said inwardly extending flange and said outwardly extending flange, an inwardly extending flange on the casing adjacent the driving wheel and means for transferring the axial thrust exerted on the driven inner member to the said flange on the casing.

17. In a horizontal metal extrusion machine comprising a casing of circular cross-section which houses or forms part of a screw thread impelling device constituted by inner and outer concentric tubular members of which the inner is driven in rotation and by which the plastic metal is driven forward and through an annular extrusion orifice constituted by inner and outer dies, a support for the inner die extending rearwardly of the driven inner member, a driving wheel mounted on the driven inner member, a torque tube coupled to said driving wheel and extending rearwardly thereof, means for applying through an aperture in the rear end of the machine casing, a drive to the rear end of said torque tube, an inwardly extending flange on said torque tube, an outwardly extending flange on a part of said inner die support extending beyond the driven member, a thrust bearing interposed between said inwardly extending flange and said outwardly extending flange, a flange on the driven member, an inwardly extending flange on the casing located between the driving wheel and the flange on the driven member, and a thrust bearing interposed between said flange on the driven member and said flange on the casing.

18. In a metal extrusion machine as specified in claim 16, at least one cradle for supporting the machine casing, a second driving wheel located to the rear of the extrusion machine casing and supported independently thereof, a flexible coupling between said second driving wheel and said torque tube, a casing for said second driving wheel, means comprising interengaging surfaces on said second driving wheel casing and the machine casing, for positively restraining the machine casing from rotating in said cradle.

19. In a metal extrusion machine as specified in claim 16, at least one cradle for supporting the machine casing, a second driving wheel located to the rear of the extrusion machine casing, supported independently thereof and coaxial therewith, a flexible coupling between said second driving wheel and said torque tube, a casing for said second driving wheel, and means for coupling

said second driving wheel casing to said machine casing whereby positively to restrain said machine casing from rotating in said cradle, said coupling means comprising projections on one of said casings and recesses on the other of said casings and heat insulating material interpolated between said projections and recesses whereby to prevent metallic contact between said casings.

20. In a horizontal metal extrusion machine comprising a screw thread impelling device, consisting of an inner member and a rotatable tubular outer member, by which plastic metal is driven forward and through an extrusion orifice, a driving wheel carried by the rotatable outer member, a machine casing comprising a central portion housing said driving wheel and subjected to thrust loads exerted by the plastic metal, said central portion being of circular cross-section except for the provision therein of two pockets located on diametrically opposite sides of said central portion, a pair of gear wheels housed one in each pocket in said casing and in engagement with said driving wheel, and means for driving each of said gear wheels.

21. In a horizontal metal extrusion machine comprising a screw thread impelling device, consisting of an inner member and a rotatable tubular outer member, by which plastic metal is driven forward and through an extrusion orifice, a driving wheel carried by the rotatable outer member, a machine casing comprising a central portion housing said driving wheel and carrying thrust loads exerted by the plastic metal on the impelling device, said central portion being of circular cross-section except for the provision therein of two pockets located on diametrically opposite sides of said central portion, a gear wheel housed in each pocket and engaging said driving wheel, means for driving each of said gear wheels, supporting feet extending one from the wall of each pocket in the central portion of the said machine casing, said pockets and said feet being symmetrical about a horizontal plane containing the machine axis.

22. In a horizontal metal extrusion machine comprising a screw thread impelling device, consisting of an inner member and a rotatable tubular outer member, by which plastic metal is driven forward through an extrusion orifice, a driving wheel carried by the rotatable outer member, a machine casing comprising a central portion housing said driving wheel and carrying thrust loads exerted by the plastic metal on the impelling device, said central portion being of circular cross-section except for the provision therein of two pockets located on diametrically opposite sides of the central portion, a pair of gear wheels housed one in each pocket and engaging said driving wheel, a pair of shafts supporting said gear wheels and extending through the walls of the pockets, means for driving each of said shafts, heat insulating material inserted between said shafts and said driving means, supporting feet which extend one from the wall of each pocket in the said machine casing, said supporting feet and pockets being symmetrical about a horizontal plane containing the machine axis, a pedestal for each supporting foot, and heat insulating material inserted between each supporting foot and its pedestal.

23. In a horizontal metal extrusion machine with a screw thread impelling device, comprising a rotatably driven tubular member within which is located a stationary member carrying an inner die at its front end past which the metal to be

extruded is driven forward in a plastic state, a machine casing housing the impelling device and a driving wheel therefor on the rotatably driven tubular member, means for transferring to the

5 said casing the axial thrust exerted on the driven member by the plastic metal and the axial thrust exerted on the said stationary die-carrying member by the plastic metal, the part of said casing in front of the point at which the thrust on the
10 stationary die-carrying member is transferred to the casing being symmetrical about the axis of the impelling device.

24. In a horizontal metal extrusion machine with a screw thread impelling device comprising
15 a rotatably driven tubular member within which is located a stationary member carrying an inner

die at its front end past which the metal to be extruded is driven forward in a plastic state, a machine casing housing the impelling device and a driving wheel therefor on the rotatably driven tubular member, means for transferring to the
5 said casing the axial thrust exerted on the driven member by the plastic metal and the axial thrust exerted on the said stationary die-carrying member by the plastic metal, the part of said casing in front of the point at which the thrust on the
10 stationary die-carrying member is transferred to the casing being symmetrical about the axis of the impelling device and also symmetrical in section in any plane containing the said axis.
